UNITED STATES PATENT OFFICE

101,154

DESIGN FOR A TRAY

Albert A. Woodfield, Centralia, Wash.

Application March 27, 1936, Serial No. 61,818

Term of patent 14 years

To all whom it may concern:

Be it known that I, Albert A. Woodfield, a citizen of the United States, residing at Centralia, in the county of Lewis and State of Washington, have invented a new, original, and ornamental Design for a Tray, of which the following is a specification, reference being had to the accompanying drawing, forming part thereof.

Figure 1 is a view in bottom plan of a tray showing my new design.

Figure 2 is a view in side elevation thereof.

I claim:

The ornamental design for a tray as shown.

ALBERT A. WOODFIELD.
